Des. 215,073
Patented Aug. 26, 1969

215,073

CROSSTIE

Philip J. McQueen, San Rafael, Calif., assignor to J. H. Pomeroy & Co., Inc., San Francisco, Calif., a corporation of Washington

Filed Mar. 18, 1968, Ser. No. 11,005

Term of patent 14 years

Int. Cl. D31; D25—01

U.S. Cl. D66—3

FIGURE 1 is a perspective view of a crosstie, incorporating my invention;

FIGURE 2 is a view in top plan thereof;

FIGURE 3 is a view in side elevation thereof;

FIGURE 4 is an enlarged view in end elevation thereof; and

FIGURE 5 is an enlarged fragmentary view in side elevation of an end portion thereof.

I claim:

The ornamental design for a crosstie, substantially as shown.
